UNITED STATES PATENT OFFICE.

LEVI W. GARRETT, OF PENDLETON, OREGON.

LATCH-OPERATING DEVICE.

1,100,553.

Specification of Letters Patent. Patented June 16, 1914.

Application filed September 3, 1913. Serial No. 737,966.

To all whom it may concern:

Be it known that I, LEVI W. GARRETT, a citizen of the United States, residing at Pendleton, in the county of Umatilla and 5 State of Oregon, have invented new and useful Improvements in Latch - Operating Devices, of which the following is a specification.

The invention relates to latch operating 10 devices, and more particularly to the class of foot controlled latch operators.

The primary object of the invention is the provision of a device of this character which can be mounted upon a door so that the 15 foot of a person can readily actuate the device for releasing the latch to permit the opening of the door.

Another object of the invention is the provision of a device of this character 20 wherein the same is readily adjustable so that it can be conveniently mounted upon doors of different heights, and which is actuated by the foot for the unlatching of the door.

25 A further object of the invention is the provision of a device of this character which is extremely simple in construction, thoroughly reliable and efficient in its purpose, and inexpensive in manufacture.

30 With these and other objects in view, the invention consists in the construction, combination and arrangement of parts as will be hereinafter fully described, illustrated in the accompanying drawing, and pointed out 35 in the claims hereunto appended.

In the drawing:—Figure 1 is a side elevation of a door casing and door mounted thereon with the latch operating device constructed in accordance with the invention

40 applied to the door. Fig. 2 is a fragmentary edge elevation of the door. Fig. 3 is a sectional view on the line 3—3 of Fig. 1. Fig. 4 is a sectional view on the line 4—4 of Fig. 1.

45 Similar reference characters indicate corresponding parts throughout the several views in the drawing.

Referring to the drawing in detail, A 50 designates a door casing of the ordinary well-known construction, and B a door which is swingingly connected to the casing for the opening and closing of the doorway. This door B carries a lock C provided with the usual finger operated latch releasing 55 member D, and upon this door is adapted

to be mounted the foot-actuated device presently described.

The foot-actuated device comprises a foot lever 5 supported upon a pivot 6 which is journaled in a housing 7, the same being 60 mounted in a suitable opening formed in the door near the lower end thereof, the lever 5 being projected beyond opposite sides of the door so that it can be actuated by the foot from the outside or inside for controlling the latch member D of the lock C carried by the door. At one side of the latch member D is arranged a rocking lever 8 which is supported upon a pivot 9 mounted in the door, one end of the lever being 65 bent at right angles to form an extension 10 terminating in a head 11 in alinement with the latch member D and adapted to contact therewith.

Connecting the foot lever 5 with the rocking lever 8 is an extensible rod comprising upper and lower sections 12 and 13, the latter being pivoted at 14 to the foot lever 5, while the section 12 is pivoted at 15 to the rocking lever 8. These sections 12 and 13 80 are formed at their overlapping ends with toothed surfaces 16 adapted to interfit with each other for the joining of the sections together and also to permit the lengthening or shortening of the rod. Embracing the 85 overlapped ends of the sections 12 and 13 of the rod is a collar 17 carrying a set screw 18 which is adapted to act upon the section for bringing the toothed surfaces 16 in locking relation to each other, it being evident 90 that on the loosening of the screw 18 the sections 12 and 13 can be adjusted with respect to each other for the lengthening or shortening of the rod.

To actuate the device it is necessary that 95 a person actuate the lever 5 at the outside of the door by pressing downwardly thereon, which will rock the lever 8, causing the head 11 to depress the latch member D for retracting the latch bolt of the lock C, thus 100 unlatching the door. In event the door is closed and the person is on the inside thereof it is necessary to press upwardly on the lever 5 with the foot which lifts the rod and causes the rocking of the lever 8 and thereby 105 depressing the member D of the lock C for retracting the latch so that the door can be readily opened.

From the foregoing it is thought that the construction and manner of operation of the 110

device will be clearly understood, and therefore a more extended explanation has been omitted.

What is claimed is:—

- 5 1. The combination with a door having a latch provided with a finger actuated releasing member projecting from one side thereof, of a latch operating device comprising a rocking lever adapted to be pivoted 10 to the door, a depending extension at one end of the lever, a head on the extension arranged for engagement with the finger actuated member, a foot lever pivoted in the door and projected beyond opposite sides 15 thereof, rods pivotally connected to the levers and having overlapping ends, and means for adjustably clamping the overlapped ends of the rods together.
- 15 2. The combination with a door having a latch provided with a finger actuated re-

leasing member projecting from one side thereof, of a latch operating device comprising a rocking lever adapted to be pivoted to the door, a depending extension at one end of the lever, a head on the extension arranged for engagement with the finger actuated member, a foot lever pivoted in the door and projected beyond opposite sides 25 thereof, rods pivotally connected to the levers and having overlapping ends, means for adjustably clamping the overlapped ends of the rods together, and intersitting teeth formed on the meeting faces of the overlapped ends of the rods.

In testimony whereof I affix my signature 30 in presence of two witnesses.

LEVI W. GARRETT.
